HOBBY HORSE FRAME

Furman F. Taylor and Floyd H. Wyman,
Westminster, S. C.

Application September 2, 1955, Serial No. 37,780

Term of patent 14 years

(Cl. D34—15)

The broken line showing of a hobby horse is for illustrative purposes only.

We claim:

The ornamental design for a hobby horse frame, as shown and described.
